UNITED STATES PATENT OFFICE.

THOMAS HARLOW AND WILLIAM ZIMMERMANN, OF BENTON CITY, MISSOURI.

COMBINATION AUTOMOBILE RADIATOR FILLER AND ORNAMENT.

Application filed August 2, 1927. Serial No. 210,107.

Generically this invention relates to funnels or fillers, but more especially it is directed to the type adaptable for attachment to radiators of motor cars.

5 The principal object of this invention is the provision of a combination radiator filler and ornament which may be attached to the radiator filling neck as a cap, and when in open position constitutes a funnel or filling 10 device, and when closed a radiator ornament.

Another object of this invention is the provision of a device of this character comprising hinged elements normally constituting a seal for the air vent pipe and forming sections 15 of the ornament but operable to open position to permit escape of air from said pipe and to constitute a funnel, to prevent water from spilling upon the radiator, hood, or clothes of the operator, when the radiator 20 is being filled, the operating means also adapted to automatically maintain the sections in open or closed position as desired.

With these and other objects in view, which will become apparent as the description 25 proceeds, the invention resides in the construction, combination and arrangement of parts, hereinafter more fully described and claimed, and illustrated in the accompanying drawings, in which like characters 30 of reference indicate like parts throughout the several figures, of which:

Figure 1 is a fragmentary perspective view of a portion of an automobile radiator showing our improved ornamental radiator filler 35 cap in operative position:

Figure 2 is a longitudinal vertical section of the device illustrated in Fig. 1 partly in elevation;

Figure 3 is a transverse sectional view 40 taken on the line 3—3 of Fig. 2, looking towards the rear;

Figure 4 is a similar view to Fig. 3 showing the movable sections in open position to constitute a funnel; and

Figure 5 is a transverse sectional view 45 taken on the line 5—5 of Fig. 2, looking towards the front and showing the air vent pipe closed.

In devices of this character heretofore in 50 use it has generally been necessary to either sacrifice the ornamental radiator cap for some special filling means or to suffer the inconvenience of filling the radiator in the usual manner, and it was to overcome such 55 deficiencies and to provide an ornamental radiator cap that would at the same time

constitute an efficient filling device to prevent spilling or splashing of water over the radiator or clothes of the operator during the filling of the radiator that we designed the 60 combination ornamental cap and filler forming the subject matter of this invention.

In the illustrated embodiment characterizing this invention there is shown an automobile radiator 1, filling neck or opening 2, and 65 hood 3 of conventional design.

In order to present an ornamental and artistic appearance as well as to constitute a practical funnel or filler, the device may comprehend any desired configuration, and 70 while in the present instance it is fashioned to simulate the appearance of a dog 4, it could with equal effectiveness represent a chicken, bird, or the like.

The body 5 of the device 4 is hollowed out 75 to form the substantially cylindrical chamber 6, the upper wall of the cylinder or back of the device 4 being formed with complementary movable sections 7 and 8, respectively.

Hingedly connected to the body portion on 80 either side in a substantially central horizontal plane, and formed along their lower edges with spaced strap-like portions bent upon themselves to form hinge loops 9, adapted to dovetail with similarly formed 85 loops 10 of the body 5 to receive the hinge rod 11. The said sections normally contact along their upper edges, as at 12, to form a closure for said chamber 6 and to prevent a comparatively unbroken contour of the device. 90

Welded or otherwise suitably secured to each end of the sections 7 and 8 at right angles thereto are semi-elliptical end plates 13, which when said sections are in open or filling position, prevent water from splashing or spilling over the ends of the device. The free ends of the plates 13 at one end of the device are apertured as at 14 to receive the lateral projection 15 of the spring arms 16, the upper ends of said arms extending through aperture 16, and being suitably secured in the operating handle 17, which latter normally constitutes the tail of the dog. 100

The said device or dog 4 is formed with a depending tubular neck 18 threaded as at 19 for engagement with the usual filling neck 2 of the radiator and is eccentrically positioned with respect to the device so 110 that the latter will not interfere with the raising and lowering of the hood 3. An

air vent pipe 20 extends from within the radiator 1, laterally to the front end of the chamber 6 and upwardly to a point where the upper end will be sealed by the section 5 7 when in closed position, as clearly shown in Fig. 5 of the drawings, but when the section is in open position air can freely pass from said tube during filling of the radiator, as is well understood.

10 In order to prevent boiling over of the radiator should it become overheated, and to otherwise seal the same, a threaded plug 21, is adapted for threaded engagement with the tubular neck 18, and is formed with 15 an insulated handle 22, so that the same may be expeditiously removed when in a heated condition.

While the operation is clear from the above description, it might be well to state 20 that the device normally constituting an ornamental cap is converted into a funnel-like filling device by simply elevating handle 17 which through the instrumentality of spring arms 16 and end plates 13 opens sections 7 25 and 8 outwardly to expanded or filling position, whereupon plug 21 may be removed and the radiator filled.

In this connection it will be observed that 30 the spring arms 16 automatically operate when in lowered position to maintain the sections 7 and 8 firmly closed and when in elevated position to similarly maintain them in open position.

It is apparent from the above description 35 that we have designed a unique and novel combination ornamental radiator cap and filler, easily attachable as a radiator cap, artistic in appearance, simple in construction, manufacturable at a negligible cost, 40 and efficient for the purposes intended.

Although in practice we have found that 45 the form of our invention illustrated in the accompanying drawings and referred to in the above description, as the preferred embodiment, is the most efficient and practi-

cal; yet realizing the conditions concurrent with the adoption of our invention will necessarily vary, we desire to emphasize that various minor changes in details of construction, proportion and arrangement of parts, 50 may be resorted to within the scope of the appended claims without departing from or sacrificing any of the principles of this invention.

Having thus described our invention, what 55 we desire protected by Letters Patent is as set forth in the following claims:

1. An article of manufacture comprising a cylindrical body, an externally threaded nipple formed integral with the body and adapted to seat in the internally threaded opening of a radiator, the upper portion of the body being divided into segments, the segments being hinged to the free edges 60 of the lower portion of said body, and means in connection with the segmental portions to position the latter when operated in one direction to form a continuation of the lower portion, and in the opposite direction to extend the segments to constitute a trough-like opening.

2. An article of manufacture comprising a cylindrical body closed at both ends, a threaded nipple formed integral with the body and adapted for engagement with the threaded opening of a radiator, the upper portion of the body being divided into complementary segments, the segments being longitudinally hinged at their lower edges and the free edges of the lower portion, said 75 segments provided with end plates and means 80 connected to certain of the end plates whereby vertical movement downwardly of such means will bring the segments into closed relation, and when operated in the opposite 85 direction will expand the segments to form a trough-like funnel.

THOMAS HARLOW.
WILLIAM ZIMMERMANN.
